UNITED STATES PATENT OFFICE

ARTHUR M. TROGNER, OF MAPLEWOOD, NEW JERSEY, ASSIGNOR TO WIRED RADIO, INC., OF NEW YORK, N. Y., A CORPORATION OF DELAWARE

DESIGN FOR AN ESCUTCHEON FOR WIRED RADIO TUNER

Application filed February 14, 1930. Serial No. 34,541. Term of patent 14 years.

To all whom it may concern:

Be it known that I, ARTHUR M. TROGNER, a citizen of the United States, residing at Maplewood, in the county of Essex and State of New Jersey, have invented a new, original, and ornamental Design for Escutcheon for Wired Radio Tuner, of which the following is a specification, reference being had to the accompanying drawing, forming part thereof.

In the drawing Fig. 1 is an elevation and Fig. 2 a plan view of an escutcheon for wired radio tuner, showing my new design.

I claim:

The ornamental design for an escutcheon for wired radio tuner, as shown.

ARTHUR M. TROGNER.
